UNITED STATES PATENT OFFICE.

FRANK R. WEST, OF NEWARK, NEW JERSEY.

INTERNAL-COMBUSTION ENGINE.

Application filed September 18, 1924. Serial No. 738,465.

The present invention relates to improvements in internal combustion engines, and it has for its object primarily to provide a novel and improved cylinder head or combustion chamber therefor, whereby higher compression pressures than those commonly used may be employed successfully, thus increasing the power and efficiency of the engine, the shock of the explosions will be cushioned or absorbed to a desirable degree, thus producing smoother operation of the engine, and reducing vibration and strains, and carbonizing of the engine is avoided or reduced to a minimum.

Another object of the invention is to provide a novel and improved construction and arrangement of the cylinder head with respect to the cylinder block or casting, whereby the manufacture of the engine is simplified and rendered less expensive.

To these and other ends the invention consists in certain improvements and combinations and arrangements of parts as will be hereinafter more fully described, the features of novelty being pointed out particularly in the claims at the end of the specification.

In the accompanying drawings:—

Figure 1 represents a section taken axially through a portion of an internal combustion engine constructed in accordance with one embodiment of the present invention;

Figure 2 illustrates the structure shown in Figure 1 as viewed from the right in said figure, the cylinder head being shown in section on the line 2—2 of Figure 1;

Figure 3 is a view similar to Figure 1 showing another embodiment of the invention;

Figure 4 is a view similar to Figure 3 showing a modified form of cylinder head embodying the invention; and

Figure 5 represents a section on the line 5—5 of Figure 4.

Similar parts are designated by the same reference characters in the several views.

The present invention is applicable generally to internal combustion engines of the various types, such, for example, as those used in automobiles. The preferred embodiments of the invention are illustrated to the accompanying drawings and will be hereinafter described in detail, but it is to be understood that the invention is not restricted to the precise constructions shown

as equivalent constructions are contemplated, and such will be included within the scope of the claims.

In the present instance, 1 represents the cylinder block or casting which may be provided, as usual, with a water jacket 2, 3 designates the piston which reciprocates therein, and 4 designates the intake and exhaust valves which control, in the well known way, the admission of fuel mixture to the combustion chamber and the exhausting of the products of combustion therefrom. The cylinder block, piston and valves may be of the usual or conventional construction, although, in the present instance, the valves are shown inclined toward the cylinder bore at their upper ends. The combustion chamber 5 is formed in the cylinder block or casting, it comprising a cavity which is formed in the cylinder block below the top 6 of the cylinder block. The head 7 which is of the detachable type and may be secured to the top of the cylinder block by the usual bolts or screws 8 is formed with a cavity 9 which is adapted to contain water from the cooling or circulating system of the engine, it communicating, for example, with the jacket 2 of the cylinder block through passages 10 and 11 in the block and head, respectively, which register when the head is applied.

The present invention provides a wall for the combustion chamber which is comparatively thin and is directly cooled by the water of the circulating system whereby such wall will be maintained at a relatively lower temperature than that of the relatively thick cast iron walls which have heretofore formed the walls of the combustion chamber. The means for accomplishing these results consists preferably of a thin plate or diaphragm 12 composed preferably of metal in flat form, this plate or diaphragm being interposed and clamped in place between the head and the top of the cylinder block so that it forms a septum or wall between the combustion chamber 5 and the water chamber 9. Suitable gaskets 13 may be applied at opposite sides of the plate to insure a pressure-tight and water-tight joint around the margin of the plate or diaphragm, and the latter, as well as the gaskets, being slotted or apertured to avoid obstructing the water passages 10 and 11.

The plate or diaphragm 12, which, as

shown, is relatively thin, forms one wall of the combustion chamber, and it is maintained at a relatively low temperature by the cooling water which is in contact with its opposite side. In consequence, the combustion chamber of the engine may be proportioned to produce a higher compression pressure than that heretofore commonly used without causing detonation or pre-ignition 5 knocks. Moreover, the formation of carbon on the combustion chamber side of the plate or diaphragm is avoided or minimized owing to its relatively low temperature as maintained by the cooling water, researches 10 having established that carbon resulting from the combustion of the fuel in internal combustion engines will not form or accumulate readily on a cool metallic surface.

The plate or diaphragm 12 is preferably 20 sufficiently thin to enable it to flex or yield slightly under the influence of the explosion pressure developed in the combustion chamber, this yielding or flexing of the plate or diaphragm resulting in cushioning or absorbing to a desirable degree the shocks produced by the successive explosions taking place within the combustion chamber. The inertia of the body of cooling water at the upper side of the plate or diaphragm will 30 assist in cushioning or absorbing the shocks of the explosions, and such body of water will also support the plate or diaphragm and assist it in sustaining the forces produced by the explosions taking place within the combustion chamber. Moreover, by using a plate or disk as a combustion chamber wall which is capable of yielding or flexing under the influence of the explosions taking place within the combustion chamber, the 35 plate or diaphragm will be set into vibration in consequence of the successive explosions taking place, and this vibration of the plate or diaphragm will tend to shake off any surplus oil or carbon which may be thrown thereon, it thus avoiding the accumulation of oil or carbon.

If desired, a spring of suitable form may be provided to assist the plate or diaphragm in sustaining the force produced by the 40 explosions within the combustion chamber, a coil spring 14 being shown for this purpose in Figure 3, the spring being interposed between the head and the side of the plate or diaphragm opposite to the side thereof at 45 which the combustion chamber is located. In using such a spring, the spring as well as the plate or diaphragm will yield or flex under the influence of the explosions, but the spring will strengthen the plate or diaphragm and will assist the latter in returning to its normal or flat form after each 50 explosion. In some cases, it may be desirable to employ means for limiting the degree of flexure of the plate or diaphragm in consequence of the explosion. Such a construc-

tion is shown in Figures 4 and 5 wherein the cylinder head is formed with ribs 15 which are contained within the water cavity at the upper side of the plate or diaphragm, the ribs extending to points nearly in contact 70 with the plate or diaphragm when the latter is in its normal or unflexed form, the ribs, however, being sufficiently close to the upper side of the plate or diaphragm to provide abutments against which the plate or diaphragm may bear when the latter is flexed under the influence of explosions within the combustion chamber. The ribs will thus serve to prevent undue flexing of the plate or diaphragm and will prevent it from 80 being ruptured or blow out by explosion pressures produced within the combustion chamber.

Preferably, the dividing line between the cylinder block and head is arranged at an 85 obtuse angle with respect to the axis of the cylinder bore and piston, substantially as is shown. The plate or diaphragm 12, in consequence, will slope upwardly or in a direction away from the head of the piston at the side of the cylinder block where the valves are located. This enables a combustion chamber of efficient form to be provided above the piston and valves without the necessity of forming separate pockets 90 for the valves, which pockets are objectionable. By arranging the valves so that they converge at their upper ends toward the cylinder bore, the valves may, as shown, operate directly within the largest part of the 100 combustion chamber. By forming a cavity in the end of the cylinder block and providing a plate or diaphragm as hereinbefore described to form the top wall of the combustion chamber, the manufacturing cost of 105 the engine is reduced in consequence of the simplification of the mechanical operations required, and furthermore, the combustion chamber may be readily machined to a predetermined volumetric capacity.

I claim as my invention:—

1. An internal combustion engine having a combustion chamber a wall of which is constituted by a relatively thin substantially flat flexible plate of uniform thickness 115 throughout its area and which divides the combustion chamber from the water space of the engine.

2. An internal combustion engine having a combustion chamber a wall of which is constituted by a thin flexible sheet of metal of uniform thickness throughout its area and having an area at one side exposed to the cooling water of the engine, which area is substantially equal to the area at the opposite side of the sheet which is exposed to the combustion chamber.

3. An internal combustion engine having a combustion chamber a substantially flat wall of which is of uniform thickness 130

throughout its area and which is flexible out of its normal plane under the influence of the explosions taking place in said chamber.

4. In an internal combustion engine comprising a cylinder block having a combustion chamber therein and a separately formed head, said cylinder block and head having plane joining surfaces, a plate of uniform thickness throughout its area having its marginal portions interposed between said joining surfaces of the cylinder block and head and forming a wall of the combustion chamber which is flexible outward of its normal plane under the influence of the explosions taking place therein.

5. In an internal combustion engine comprising a cylinder block having a combustion chamber therein and a head therefor having a water chamber therein, a substantially flat vibratory plate of uniform thickness throughout its area interposed between the cylinder block and head and dividing the combustion chamber of the former from the water chamber of the latter.

25 6. In an internal combustion engine comprising a cylinder block having a combustion chamber therein and head therefor having a cooling water chamber therein, plane joining surfaces being formed on said block and head, a flat flexible plate having a marginal portion co-extensive with the full areas of said joining surfaces and clamped between them, said plate forming at one side a wall of the combustion chamber and at its opposite side a wall of the combustion chamber

and at its opposite side a wall of substantially equal area for said water chamber.

7. An internal combustion engine embodying a cylinder having a joining surface at its combustion chamber end which lies in a plane at an obtuse angle to the cylinder axis, and intake and exhaust valves located adjacent to the combustion chamber end of the cylinder and within the obtuse angle formed between the plane of said joining surface and the cylinder axis, a flat relatively thin flexible plate forming the combustion chamber wall applied to said joining surface, the opposite surfaces of said plate presenting equal areas thereof to the combustion chamber and a cooling water space respectively.

8. In an internal combustion engine of the class having intake and exhaust valves arranged at a side of the cylinder, a cylinder provided with a flexible cylinder head which presents a thin wall section to the combustion chamber and is water jacketed on the upper side of said thin wall section to an extent approximately equal to the area of the under side of said wall section which is exposed to the heat of the combustion chamber, the top of the cylinder forming a joint with the head, which joint is inclined with respect to the axis of the cylinder bore from a point opposite the valves toward the end of the cylinder.

In testimony whereof I have hereunto set my hand.

FRANK R. WEST.
